UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS.

DUMP-CAR.

964,749.

Specification of Letters Patent. Patented July 19, 1910.

Application filed July 1, 1909. Serial No. 505,341.

To all whom it may concern:

Be it known that I, ARGYLE CAMPBELL, a citizen of the United States, residing in Chicago, in the county of Cook and State of Illinois, have invented a new and useful Improvement in Dump-Cars, of which the following is a specification.

My invention relates to improvements in dump cars.

10 My invention consists in the novel construction of parts and devices and in the novel combinations of parts and devices herein shown and described and more particularly specified in the claims.

15 In the accompanying drawing forming a part of this specification, Figure 1 is a plan view, partly broken away, of a dump car embodying my invention and Fig. 2 is a side elevation, only one half of the length 20 of the car being shown in Figs. 1 and 2 for the sake of clearness. Fig. 3 is a vertical cross section on line 3—3 of Fig. 2. Fig. 4 is a detail plan view of the ratchet mechanism. Fig. 5 is a bottom plan view of 25 same. Fig. 6 is a detail elevation of one of the ratchet mechanisms, partly in vertical section on line 6—6 of Fig. 5. Fig. 7 is a detail plan view and Fig. 8 a detail vertical section illustrating a modification on line 30 8—8 of Fig. 7.

In the drawing, 1 represents a dump car, 2 the center sills, 3 the upright sides, 4 the inclined ends and 5, 5 and 6, 6 the inclined sides of longitudinally arranged hopper bottoms 7, 8, one set of said hoppers being on each side of the longitudinal center or middle line of the car body, the two central inclined sides 6, 6 of the hoppers extending over the center sills 2, 2 and meeting at the longitudinal middle line of the car. The hoppers 7, 7 and 8, 8 on each side of the longitudinal middle of the car are divided or separated transversely from each other by one or more, preferably three, inverted V, 45 cross hopper sheets 9, 9. The discharge openings 10 of the hoppers 7, 8 are closed by doors 11, each hinged at its outer longitudinal edge to one of the outer inclined sides 5 of the hoppers 7, 8 so that each of the 50 hoppers may be centrally dumped by hinges 12.

The means for opening and closing the several doors 11 preferably consists of operating shafts 13, one for the doors of each

longitudinal set of hoppers 7, 8, and arranged under the longitudinal center hopper sheets 6, 6, which extend over the center sills 2, and door operating mechanism on said shafts for the several doors arranged under the cross hopper sheets 9, each door 60 operating mechanism preferably consisting of a polygonal winding drum 14 on the shaft 13 in connection with links 15, 16, 17, 18 and 19 adapted to wind around said drum, the link 18 having a locking shoulder 65 20 adapted to engage a locking shoulder 21 on the drum, and the link 19 having a bent end 22 hinged to the link 18 directly over the center of the drum when the door is closed and to which link 19 the door is pivotally connected by a strap 23.

Each of the operating shafts 13 is furnished with a bevel gear 24 at its outer end which meshes with a bevel gear 25 on the ratchet shaft 26. The ratchet shaft 26 is 75 upright, and is journaled under the inclined end sheet 4 of the dump car. It is provided at its upper end with a ratchet 27 having a series of rectangular flat faced teeth 28, the teeth being preferably 8 in number. 80 The ratchet shaft is turned by a fulcrum wheel 29 having a plurality of upwardly projecting fulcrums or posts 30 adapted to receive any ordinary bar or stick of wood between them as a lever for turning the 85 ratchet shaft. Each of the fulcrums or posts 30 is preferably furnished with a flange 31 at its upper end to aid in keeping the operating lever or bar in position. The fulcrum wheel 29 is furnished with one or 90 more pivoted pawls 32, each having a flat end face 33, adapted to engage the flat faced teeth 28 of the ratchet 27. By this means the dump doors may be operated very conveniently and with entire safety to the operator. 95

The longitudinal center hopper sheet or hopper sides 6, 6 have openings 35 therein registering and intersecting with the cross hopper sheets 9 and covered thereby to accommodate or receive the door operating mechanism on the longitudinally extending operating shaft 13. This enables the door operating shaft to be located under and closely adjacent to the hopper sides, and thus bring the operating shaft and the door operating mechanism substantially directly over the free or swinging edge of the door 100 105

as required, while at the same time giving to the dump car a maximum load carrying space.

In the modification shown in Figs. 7 and 8, I have illustrated my invention as applied to a dump car without cross hopper sheets, in which case the openings 35 in the central, longitudinal hopper sides 6, 6 for the door operating mechanism to project through are closed by cast metal, pressed steel, or other covers or housings 34, preferably of a concave shape. These recessed covers or housings 34 correspond in principle and function to the end portions of the cross hopper sheets.

The doors may be operated up or down as occasion may require, by simply swinging the pawls to the right or left so that they are in position to engage the opposite flat face of the ratchet teeth.

I claim:—

1. In a dump car, the combination with a dump car body having discharge openings on each side of its longitudinal center, and central longitudinally extending inclined hopper sides, and provided with cross hopper sheets transversely separating said discharge openings, doors hinged at their outer side edges for closing said openings to adapt the car for central dumping, longitudinal operating shafts for said doors extending under said central hopper sides and provided with operating mechanism for said doors arranged under said cross hopper sheets substantially as specified.

2. In a dump car, a dump car body adapted for central dumping, having openings on each side of its longitudinal center, and central, longitudinal hopper sides and cross hopper sheets transversely separating said openings, doors hinged at their outer side edges for closing said openings, and a longitudinally extending operating shaft under said longitudinally extending hopper sides and door operating mechanism under said cross hopper sheets, substantially as specified.

3. In a dump car, the combination with a dump car body having discharge openings on each side of its longitudinal center, and central, longitudinally extending inclined hopper sides, and provided with cross hopper sheets transversely separating said discharge openings, doors hinged at their outer side edges for closing said openings to adapt the car for central dumping, longitudinal operating shafts for said doors extending under said central hopper sides, and provided with operating mechanism for said doors arranged under said cross hopper sheets, said door operating mechanism com-

prising a polygonal winding drum and links connected thereto and to the doors, the drum and one of said links having locking shoulders, substantially as specified.

65

4. In a dump car, the combination with a dump car body having a discharge opening and a door for closing the same, and an operating shaft and connections for operating the door, of a ratchet and a fulcrum wheel carrying a pawl, and provided with a plurality of fulcrum posts to receive an operating lever, substantially as specified.

5. In a dump car, the combination with a door and its operating shaft and connections for operating the door from said shaft, of a ratchet shaft, a ratchet thereon, a fulcrum wheel provided with a pawl engaging the ratchet and furnished with a plurality of fulcrum posts to receive a lever, substantially as specified.

6. In a dump car, the combination with a door and its operating shaft and connections for operating the door from said shaft, of a ratchet shaft, a ratchet thereon, a fulcrum wheel provided with a pawl engaging the ratchet and furnished with a plurality of fulcrum posts to receive a lever, said ratchet having flat faced teeth, and the pawl having a flat end face adapted to fit against the flat faces of the teeth, substantially as specified.

7. In a dump car, a dump car body adapted for central dumping and having openings on each side of its longitudinal center and central longitudinal hopper sides, doors hinged at their outer side edges for closing said openings, and a longitudinally extending operating shaft under and closely adjacent to said longitudinally extending hopper side, and a door operating mechanism projecting above and inside of the plane of said hopper side, substantially as specified.

8. In a dump car, a dump car body adapted for central dumping and having openings on each side of its longitudinal center and central longitudinal hopper sides, doors hinged at their outer side edges for closing said openings, and a longitudinally extending operating shaft under and closely adjacent to said longitudinally extending hopper side, and a door operating mechanism projecting above and inside of the plane of said hopper side, said hopper side having an opening and a recessed cover for said opening to accommodate said door operating mechanism, substantially as specified.

ARGYLE CAMPBELL.
